CARRIER STAND FOR OUTBOARD MOTORS

Frederick J. Vickery, Western Springs, Ill.

Application June 16, 1947, Serial No. 754,982

5 Claims. (Cl. 280—36)

1

The invention pertains to a structure providing a collapsible or foldable stand and carrier for use in transporting a detached outboard motor easily and quickly over short distances.

The invention has for a principal object the provision of an improved carrier stand embodying a lightweight structure comprising a pair of frame sections connected together in such manner that the frames may be collapsed or folded into a compact arrangement for packaging or to be transported by itself and for arrangement in a position in which the frame sections are spread apart to provide a generally triangular structure adapted to support a detached outboard motor, one of the frames being wheeled so that the structure, with the motor mounted thereon, may be easily moved from place to place. Other important objects of the invention reside in the provision of: a lightweight construction that may be made inexpensively of relatively few parts; a frame structure in which the means for mounting the motor is so arranged as to assist in spreading apart the frames for the purpose of setting up the structure as a stand; novel means whereby the user of the structure may simply and easily spread the frames apart and lock the frames in spread-apart position; and the relation of the parts of the frame together in such manner that the entire structure when folded or collapsed may be packaged for shipment in a container of a size not heretofore deemed practical.

The foregoing and other objects will appear as a complete disclosure of the invention is made in the following detailed description and accompanying sheets of drawings in which:

Fig. 1 is a side elevational view showing in full lines the structure as a carrier stand with the frame sections spread apart, a conventional outboard motor being illustrated in dotted lines and intermediate positions of the frame sections being indicated in dot-dash lines;

Fig. 2 is a side view of the structure, on a reduced scale, showing the carrier stand completely folded or collapsed, a shipping container being indicated in broken lines;

Fig. 3 is a rear view of the structure shown in Fig. 1, the outboard motor being omitted; and

Fig. 4 is a perspective exploded view on an enlarged scale of the linkage connected between the frames for controlling the folding and unfolding of the frames.

The carrier stand comprises a first frame 10 formed generally as an elongated rectangular structure having a pair of parallel, preferably tubular, side frame members 11 cross connected

2

at their lower ends by means including a transverse axle 12 at each outer end of which is journaled a wheel 13. The axle includes a pair of snap rings 14, one inside each tubular member 11 for preventing inward movement of the tubular members on the axle. Each wheel 13 is spaced from its proximate member 11 by a short spacer 15. The upper end of the frame section 10 is provided with means on which may be temporarily mounted a detached outboard motor of any conventional type. In the present case, this means takes the form of a relatively wide board 16 extending transversely between upper portions of the frame members 11 and secured thereto by a plurality of wood screws 17.

The motor, indicated in dotted lines in Fig. 1, is shown as including a clamp 18 that engages the mounting board 16 when the motor is mounted on the carrier stand. The clamp 18 is, of course, the clamp that is used for attaching the motor to a small boat.

The lower end of each tubular member 11 is bent or displaced rearwardly from the general plane of the frame section 10, the lower portions 25 that carry the axle 12 being thus in the form of bent extensions, designated generally by the numeral 19.

The carrier stand further includes a second frame section designated in general by the numeral 20 and formed preferably as an inverted U having opposite parallel legs 21 and an upper transverse bight 22. Each leg 21 of the frame section 20 is provided at its lower end with a cap or foot 23, preferably of rubber or the like, 35 for the purpose of engaging the ground or a floor. The frame section 20 is pivoted to the frame section 10 on a transverse axis passing generally through the mounting board 16. The pivoting means is accomplished in this case by a pair of coaxial lag screws 24 passed respectively through upper portions of the legs 21 of the frame section 20 and upper portions of the tubular members 11 of the frame section 10, the lag screws entering the mounting board 16. A washer or spacer 25 is positioned on each screw 24 between the proximate side frame members of the frame sections 10 and 20 so that the frames may be easily folded and unfolded between the positions shown in Figs. 1 and 2.

50 The frame section 20 is likewise of tubular construction and the upper portion thereof that includes the bight 22 is bent or displaced rearwardly away from the general plane of the frame section 20 as at 26. The bent extension portion 26 of the frame 20 is directed away from

the frame in the same direction as are the bent extensions 19 on the frame section 10. The purpose of this arrangement is best illustrated in Fig. 2, wherein the carrier stand is shown as folded or collapsed, the frame sections 10 and 20 being pivoted about the lag screws 24 so that the frame sections are substantially coextensive and lie substantially in the same general plane, with the exception of the frame extension portions 19 and 26 and the wheels 13. It will also be noted that the diameter of the wheels 13 is so related to the length of the frame extension 26 as to dispose the outermost portions of the peripheries of the wheels in a plane that includes the bight portion 22 of the frame section 20 and that is generally parallel to the plane of the collapsed or folded structure. The diameter of each wheel 13 is substantially equal to the length of each extension 26, whereby the carrier stand when folded will fit in a shipping container that is relatively narrow, such container being shown in dotted lines at 27 in Fig. 2. The relative dimensions of the wheels 13 and extensions 26 may, of course, be varied as desired. The proportions indicated are preferred for the purpose of enabling packaging of the folded carrier stand in a container substantially smaller than containers heretofore used.

As stated above, it is an important feature of the invention to provide means by which the frame sections 10 and 20 may be easily unfolded or moved from the folded position shown in Fig. 2 to the opened or supporting position shown in full lines in Fig. 1. For this purpose the frame section 10 has pivoted thereto at 28 one end of a link 29, the other end of which is pivoted at 30 to one end of a similar link 31. The other end of the link 31 is pivoted at 32 to the proximate frame member 21 of the frame section 20. Similar linkage is provided at the other side of the carrier stand. The links are shown in detail in Fig. 4. The link 29 includes an inturned flange or lip 33 and the link 31 includes a similar though oppositely turned flange or lip 34. The pivotal connection 30 between the links 29 and 31 includes a spacer or washer 35 for the purpose of imparting freedom of movement to the linkage.

The linkage is so arranged between the frame sections 10 and 20 that the links fold upwardly about the pivot 30 and lie one alongside of the other when the frame sections are folded. The flange 33 on the link 29 will then lie along the unflanged edge of the link 31 and, similarly, the flange 34 on the link 31 will lie along the unflanged edge of the link 29. The links, thus nested, provide stop means for preventing swinging of the frame section 20 out of parallelism with the frame section 10 when the frame sections are folded as in Fig. 2.

In the use of the structure for the purpose of carrying or transporting an outboard motor, the motor is first lifted to position and then clamped by means of the clamp 18 on the mounting board 16. The structure may remain in folded position while it and the mounted motor are transported over the ground or floor by means of the wheels 13. When the motor is mounted on the folded structure and the structure is allowed to rest horizontally on the ground, being supported by the wheels 13 and the handle 22, the motor fits readily within the side frame members 11 of the frame section 10, the open construction of the frame section being provided for this purpose among others. With the motor thus mounted,

the carrier stand may be easily transported, as in the luggage space of an automobile.

When it is desired to transport the motor to the place where it is to be mounted on a boat, the carrier stand and motor are wheeled to that location. Having reached that location, the user merely raises the carrier stand by means of the handle 22, whereupon the feet 23 on the frame section 20 will engage the ground. The greater weight of the motor depends from the mounting board 16 and below the pivot axis through the lag screws 24 and, as the frame section 20 is pivoted forwardly about the engagement between its feet 23 and the ground, the wheeled frame section 10 is caused to swing rearwardly to the position shown in dot-dash lines in Fig. 1, whereupon the linkage 29-31 is partly unfolded. The user may then reach between the separated frame sections 10 and 20 with his foot and press downwardly on the linkage at the point 30 where the links are pivoted together. The toggle action thus obtained will spread the lower portions of the frame sections further apart until the point 30 passes over-center. The proximate edges of the flanges 33 and 34 on the links 29 and 31 will engage and prevent further downward movement of the links, thus holding the links in over-center position, and there will be no accidental collapsing of the carrier stand. This feature of the invention contributes largely to the ease with which the carrier stand is used. When it is desired to collapse the carrier stand, the user may simply, with his foot, raise the links 29 and 31 about their pivots 30 so that the point 30 moves upwardly past over-center position, whereupon the frame section 10 will swing toward the frame section 20, and the entire carrier stand may be tipped rearwardly about the wheels 13 and wheeled away. The stand may also be transported in its open or folded position.

The structural and functional characteristics of the preferred form of the invention set forth are those that are considered important from the standpoint of simplicity of design, ease of use, and economy of construction. Other advantages and features of the invention, together with various modifications in construction will undoubtedly occur to those skilled in the art. It is not desired that the invention be limited to the precise details of construction and use disclosed.

What is claimed is:

1. A carrier stand for an outboard motor, comprising: a frame structure including first and second relatively collapsible generally flat frame sections each having upper and lower portions, and pivoted together adjacent their upper end portions on a transverse axis for unfolding to a stand position in which the lower end portions are spread apart, and for folding to a collapsed position in which one section lies flat on the other; means providing an angularly related frame extension at the lower end portion of the first frame directed away from the plane of said section and including portions engageable with the ground; means at the upper end portion of the first frame section including a support for carrying an outboard motor; means at the lower end portion of the second frame section for engaging the ground; means providing an angularly related extension including a handle portion at the upper end portion of the second frame section and directed away from the plane of said section toward the same side as the aforesaid extension on the first frame section; and means

for releasably locking the frame sections in their unfolded stand position.

2. The invention set forth in claim 1, further characterized in that: the ground-engaging portions on the angularly related extension of the first frame section includes a wheel on a transverse axis of such diameter as respects the angularly related extension at the upper end of the second frame section that the outer end of said extension and the outermost circumferential portion of the wheel lie substantially in a plane parallel to the frame sections when folded to collapsed position.

3. The invention set forth in claim 1, further characterized in that: the outermost portion of the angularly related extension and ground-engaging portions thereof on the first frame section, and the outermost portion of the angularly related extension and handle portion of the second frame section lie substantially in a plane parallel to the frame sections when folded to collapsed position.

4. A carrier stand for an outboard motor, comprising: a first generally rectangular frame elongated from top to bottom and having a pair of longitudinal side members cross-connected at their lower ends by means including a transverse axle and wheels thereon and cross-connected at their upper ends by means including a transverse support for carrying an outboard motor; a second frame in the form of an elongated inverted U the legs of which lie normally coextensive with the side members of the first frame and include lower end portions engageable with the ground and projecting longitudinally beyond the wheels and the bight of the U providing a transverse handle; and means pivoting the frames together intermediate their ends on a transverse axis for unfolding from a position in which the frames are generally coextensive to a position in which the lower ends of the frame are spread apart to provide a generally triangular stand supported on the wheeled axle and the ground-engaging portions of the second frame; the upper portions of the second frame legs above the means pivoting the frames together projecting angularly to those portions of such legs beneath such pivoting means so as to extend substantially horizontally over and above said transverse axle and

wheels while the frames are spread apart into the triangular stand to facilitate grasping of said bight and pivoting of the stand about said transverse axle attendant to towing said stand.

5. A carrier stand for an outboard motor, comprising: a first generally rectangular frame elongated from top to bottom and having a pair of longitudinal side members cross-connected at their lower ends by means including a transverse wheeled axle and cross-connected at their upper ends by means including a transverse support for carrying an outboard motor; a second frame in the form of an elongated inverted U the legs of which lie normally coextensive with the side members of the first frame and include lower end portions engageable with the ground and the bight of the U providing a transverse handle; means pivoting the frames together intermediate their ends on a transverse axis for unfolding from a position in which the frames are generally coextensive to a position in which the lower ends of the frame are spread apart to provide a generally triangular stand supported on the wheeled axle and the ground-engaging portions of the second frame; and means for releasably locking the frames in stand position, the lower end portions of the side members of the first frame being directed away from the general plane of said first frame to space the wheeled axle outwardly of said plane; and the upper portion of the second frame, including the handle formed by the bight of the inverted U, being directed away from the general plane of said second frame to space said handle outwardly of said frame, so that the handle and wheeled axle, when said frames are in folded position, lie at the same side of said folded frames.
